CLAIM

The ornamental design for an extruded rail for plastic fencing, as shown and described.

DESCRIPTION

FIG. 1 is a cross sectional elevation of the design of an extrusion in accordance with the present invention, in which all other cross sections and end views are identical to FIG. 1. FIG. 2 is a perspective right side illustration of the embodiment of FIG. 1, in which the opposing side view is a mirror image thereof; and,

FIG. 3 is a side elevation view thereof.

The broken lines are for illustrative purposes only and form no part of the claimed design.
